W. Jay Emerson
INVENTOR

UNITED STATES PATENT OFFICE.

WALTER JAY ENNISON, OF BROOKLYN, NEW YORK.

PARLOR BASEBALL GAME.

Application filed December 2, 1921. Serial No. 519,474.

This invention relates to baseball game devices and outfits and is in the nature of an improvement upon the game-board and outfit described and claimed in my first Patent No. 1,155,714.

In the game-board and outfit of my said patent I utilized a spinning or indicating device by which the batting, running and ball plays are determined, the result being largely a matter of chance and providing little opportunity for the display of skill. Two indicating points or lines were used and it was found that the players frequently confused these points or lines with the result that the game did not proceed in the logical and real order, causing the players to lose interest. The indicator of said patent was also provided with different sets of running and ball numbers, one set used by the runners and the other set by the other active players, and inasmuch as the contestants are alternately the runners and the other active players, there was always confusion as to which set were to be used in any instance.

In said game-board outfit I provided colored buttons to represent the players of the teams which merely rested upon the board. It was found that the buttons were frequently jarred from the positions in which they were placed, especially when the board was held in the laps of the contestants, with the result that considerable confusion and uncertainty arose. The contestants also frequently confused the runners and the basemen with one another by forgetting the color they were using at that particular time, and moved the wrong buttons, which resulted in such an extent of uncertainty that a restart was frequently necessary.

An object of the present invention is to provide an improved spinner or indicator for determining the batting, running and ball plays in which considerable skill and knowledge of the game can be exercised, in which the procedure more nearly approximates actual playing rules and actions, and which is exceedingly simple and inexpensive.

50 A further object is to provide an improved

game construction in which the likelihood of confusion of the runners and basemen is eliminated; in which accidental or unintentional movement of the ball and players is practically impossible; and generally to improve and simplify the game device of my prior patent and render the playing of the game more realistic.

Other objects and advantages will be apparent from the following description and the novel features of the invention will be particularly pointed out in claims.

In the accompanying drawing, Figures 1 and 2 are plan views of the disk; Fig. 3 is a diametral section of the disk. Fig. 4 is 65 a perspective plan view of game-board, and Figs. 5 and 6 are large views of men pieces. Fig. 7 is a representation of a ball piece to be employed in connection with the game-board.

In the illustrated embodiment the diamond in miniature is indicated upon the game-board A, the diamond being defined by small squares B, B', B² and B³ representing respectively the home plate, first base, second base and third base. The bases and home plate are connected by lines a, each having three small intermediate runners' positions a' for breaking the line into four substantially equal sections. A chain of six 80 stations b surrounds each base, over which chain the basemen are shifted in making their plays in a manner determined by an indicator or spinner. The ball position stations c at the home plate, the batter's box d, 85 the catcher's chain of six stations e, the pitcher's box of four stations f, the three umpire stations g, the runner's position a', the six chain stations of the fielders' positions h, i and j, and the six chain stations 90 of the short stop position are provided with small holes, to receive small positioning pins or pegs k upon the bottoms of miniature players l, m and n. The ball piece PB is employed to represent the positions of the 95 real ball upon the diamond, and because of its construction may be termed the peg ball, in contrast to the spinner ball SB, as shown in Figs. 1, 2 and 3. This peg ball has a peg K similar in size, form and function to that 100

of the players, and is adapted to be placed in the same holes occupied by the basemen and fielders of the out-team.

The position and movement of the players and the ball upon the board is determined by the position of the spinner ball SB upon the spinner when the disc D has ceased to rotate, the spinner ball then occupying two panels containing marginal numerals, and also located within a wider panel upon the outer rim of the spinner. These numbers are intended for placing the ball upon the diamond at the place indicating the field to which it has been batted, or the base to which it has been thrown, the position of the spinner ball determining those respective actions in accordance with the relative positions of the men and the peg ball upon the board at the time of a given spinning. Thus the large sectional numbers from 1 to 6 on the extreme outer circle of the disc may be employed exclusively for positioning the peg ball upon one of the similarly designated six positions of the fielders and basemen. At the same time as pointed out the spinner ball gives numbers with which the runners of both sides may advance either on the one side from base to base or on the other side from number to number around the series of six numbered positions at each base and field until the ball is recovered.

At each successive spinning of the disc the base runner may be moved from one hole to another in the direction of the home plate in accordance with the numbers thus selected by the spinner ball SB. The numbers upon the margin of the spinning disc and the similarly arranged marginal numbers adjacent thereto upon the portion of the spinner, because of the movement of one and the stationary position of the other, make it possible to predetermine practically all movements of a baseball game, which could not be done unless a part of these numbers were permanently attached to the larger or sectional numbers 1 to 6, as shown, these numbers 1 to 6 being used for positioning the part of the marginal numbers having a partially permanent and partially variegated relationship therewith. The players *l* are basemen and have a post suggestive of a baseman. The players *m* are used as batters and runners and represent a player running with arms extending forwardly. These players *m* are provided with a notch *m'* between the upper faces of the arms and the chest so as to receive and support a miniature bat in a characteristic batting posture. The bat may be removed after the ball has been batted and the player starts toward first base. The runners and basemen are so different in appearance and posture that the contestants rarely if ever mistake the players and move the wrong one. The other

players *n* have an appearance and posture suggestive of their duties so as to provide a very realistic setting, and I have found that this has a marked psychological effect upon the contestants and greatly increases the interest in the playing of the game. The pins or pegs upon the ball and players prevent their accidental or unintentional displacement from the positions upon which they are placed or to which they are moved.

The spinner or indicator for determining the batting and running and ball movements comprises, in the preferred and illustrated embodiment, a shallow pan *P* with a centrally upstanding pin *p* on the bottom wall. A disk *D* with a spinning button *o* carried centrally thereof is mounted to rotate upon the pin *p*. The annular portion of the bottom wall of the pan surrounding the disk is divided into major and minor graduations *Q* and *q* respectively. The major graduations are each a sixth of a circle in extent and minor graduations are each a fourth of a major graduation. The major graduations are marked consecutively from 1 to 6 and the minor graduations are selectively marked with the numerals 1 to 4 and certain of these, as *q'*, are given a special designation for a purpose to be explained hereinafter. The periphery of the disk is provided with graduations *r* having preferably the same angular value as the graduations *q*. These graduations are given selective values ranging from no value at all to the value 4 and the values above zero are inscribed thereon.

Within the line of these graduations the disk is provided with groups of six shallow depressions *s* which may be stamped or pressed therein, one group for each of the three bases, the three field positions and short stop. Sub-groups of two of each of these groups are connected together by arrows which extend to the graduations of the disk. These main groups are marked with distinguishing characters such as *L*, meaning left field, 1, 2 and 3, meaning first, second and third bases, *S* meaning short stop, *R* meaning right field, *CF* meaning center field, and *C* meaning catcher.

The bottom wall of the pan between the periphery of the disk and the flange or side wall slopes slightly downwardly, as does also the peripheral portion of the disk, but in an opposite direction so as to provide a shallow trough between them toward the bottom of which the spinner ball SP tends to roll. The graduations of the disk and the minor graduations of the pan are preferably marked off by small ridges *t*, which are preferably formed by pressing them from the material (preferably metal) of the pan and disk. These ridges form semi-pockets for clearly defining the various positions of the spinner ball. When the disk is rotated,

the ball in the trough is given a spin around the pan and the position in which it stops determines certain of the plays.

For an extended explanation of the manner in which the game is played, reference may be had to my said prior patent, and the explanation herein given will be directed to those features which are modified by the present construction changes.

Having described my invention, what I claim is:

1. An indicator for baseball game-boards comprising a shallow pan, and a disk of less diameter than the pan mounted to rotate within the pan close to and flat against the bottom, said pan having in the annular portion surrounding the disk two sets of graduations with indicia thereon, said disk having graduations and indicia on its periphery co-operating with sets of graduations of the annular portion in determining plays on the game-board.

2. An indicator for baseball game-boards comprising a shallow pan, a disk of less diameter than the pan mounted to rotate within the pan close to and flat against the bottom, said pan having in the annular portion surrounding the disk two sets of graduations with indicia thereon, said disk having graduations and indicia on its periphery co-operating with sets of graduations of the annular portion in determining plays on the game-board, and also having on its face a plurality of shallow depressions arranged in groups, one group for each field position.

3. An indicator for baseball game-boards comprising a shallow pan, a disk of less diameter than the pan mounted to rotate within the pan close to and flat against the bottom, said pan having in the annular portion surrounding the disk two sets of graduations with indicia thereon, said disk having graduations and indicia on its periphery co-operating with sets of graduations of the annular portion in determining plays on the game-board, and also having on its face a plurality of shallow depressions arranged in groups around the same with arrows running from sub-groups of each group to the graduations of the periphery.

4. An indicator for baseball game-boards comprising a shallow pan, a disk of less diameter than the pan mounted to rotate within the pan close to and flat against the bottom, said pan having in the annular portion surrounding the disk two sets of graduations with indicia thereon, said disk having graduations and indicia on its periphery co-operating with sets of graduations of the annular portion in determining plays on the game-board, having on its face a plurality of shallow depressions arranged in groups around the same with arrows running from sub-groups of each group to the

graduations of the periphery, and a small spinner ball to be batted around the pan and into one of the depressions to determine to what field position the game ball should be moved.

5. An indicator for baseball game-boards comprising a shallow pan, a disk of less diameter than the pan mounted to rotate within the pan close to and flat against the bottom, and a small ball in said pan, said pan having in the annular portion surrounding the disk two sets of graduations with indicia thereon, said disk having graduations and indicia on its periphery co-operating with sets of graduations of the annular portion in determining plays on the game-board, the annular portion of the pan and the peripheral portion of the disk forming a shallow annular trough to carry the ball into contact with both the disk and pan and spin it when the disk is rotated.

6. An indicator for baseball game-boards comprising a shallow pan, a disk of less diameter than the pan mounted to rotate within the pan close to and flat against the bottom, and a small ball in said pan, said pan having in the annular portion surrounding the disk two sets of graduations with indicia thereon, said disk having graduations and indicia on its periphery co-operating with sets of graduations of the annular portion in determining plays on the game-board, the annular portion of the pan and the peripheral portion of the disk forming a shallow annular trough to carry the ball into contact with both the disk and pan and spin it when the disk is rotated, the graduations of both disk and pan having radial ridges to form lines of demarcation and semi-pockets.

7. An indicator for baseball game-boards comprising a shallow pan, and a disk of less diameter than the pan mounted to rotate within the pan close to and flat against the bottom, said pan having in the annular portion surrounding the disk major graduations, and also minor graduations adjoining the periphery of the disk, said disk having peripheral graduations co-operating with the minor graduations of the pan in determining certain of the plays on the game-board.

8. An indicator for baseball game devices comprising a shallow pan, and a spinner disk of less diameter than the pan mounted to rotate horizontally therein above the bottom wall, said pan having major and minor graduations around the periphery of the disk, certain of the minor graduations having characteristics distinguishing it from the others of the minor graduations, the peripheral portion of the disk having graduations thereon co-operating with the minor graduations of the pan.

9. In a baseball game device, a board having thereon a representation of a miniature diamond, and a miniature player having the suggestive characteristics of a runner and 5 also having means to receive and removably support a miniature bat in a manner suggestive of a batter.
10. In a baseball game device, a board having thereon a representation of a miniature diamond, and a miniature player having 10

ing the suggestive characteristics of a runner with forwardly disposed arms and also having a notch between the upper side of the arms and the chest for receiving and removably supporting a miniature bat in a 15 manner suggestive of a batter.

In testimony whereof I have hereunto set my hand.

WALTER JAY ENNISSON.
